Mathias W. Baldwin of Philadelphia
Letters Patent

The Schedule referred to in these Letters Patent and making part of the same containing a description in the words of the said Mathias W. Baldwin himself of his improvement in the manufacture of wheels for Locomotive Engines and Cars to run upon Rail Roads.

To all whom it may concern, Be it known, that I Mathias W. Baldwin of the City of Philadelphia, have invented a new and useful manufacture of wheels for Locomotive Engines and Cars to run upon rail roads, and that the following is a full and exact description of my said invention.

Instead of making the wheels for the carriages of Locomotive Engines and of other cars or carriages to be used upon rail roads of cast iron or of a combination of cast and wrought iron, or of wood combined with cast or wrought iron or with both as they have been heretofore made, I cast the rims of such wheels as well in most instances as the spokes and hubs or naves in one piece with the rims of a composition of metal known to workmen under the name of hardened brass or gun metal. It is not necessary for me to designate the proportions in which the respective metals are mixed, which form the hardened brass, or gun metal, as these will vary with the degree of hardness desired in the rim or head of the wheel in a manner well known to those conversant with the casting of brass and its compounds.

Where it is desirable to increase the adhesion between the rail and the wheel it may be found necessary to make the wheel proportionably softer by decreasing the quantity often entering into the composition of them or even to cast them of soft brass or copper entirely. I do not intend to confine myself to any particular

76 UX

far from of the head of the wheel of the spokes and hubs, but to modify it in such way as experience may suggest to be the best adapted to the particular carriage to the particular carriage or road to which the wheel is to be applied. I intend sometimes also to cast the rim of the wheel of each meter without spokes but furnished with such flanches, lugs, mants or projections as shall enable me to attach thereto spokes of wood iron or other material. My claim to an exclusive privilege is not entirely upon a new manufacture of such wheels by substituting for their rims or for every part of them a new material as herein before set forth, the utility of which consists in its being better adapted to the purpose which they are intended to answer in running upon rail roads.
